UNITED STATES PATENT OFFICE.

ALBERT B. GULLY, OF STRATFORD, CONNECTICUT.

DOORSTOP.

Application filed July 2, 1923. Serial No. 648,982.

The present invention relates to an improved door stop, and has for its object to provide a device of this character by means of which swinging doors, particularly garage doors, may be effectually held in open position. A further object is to provide such a device, having a hinged check member adapted to be swung into operative and inoperative positions, and which, when in operative position, will not bear directly on the hinge pin, so that wear thereon and looseness will be minimized, and a more positive check is provided. A further object is to provide a device in which the check member will be held against swinging to a vertical position, when in operation, so that it will be effectual in soft or uneven ground.

With the above and other objects in view, an embodiment of the invention is shown in the accompanying drawings, and this embodiment will be hereinafter more fully described with reference thereto, and the invention will be finally pointed out in the claims.

25 In the drawings:

Fig. 1 is a perspective view, showing the door stop attached to a door, and in operative position;

Fig. 2 is a vertical sectional view, the check member being shown in operative position, and partially broken away;

Fig. 3 is a similar view, the check member being shown in inoperative position; and

Fig. 4 is a plan view of the base plate employed.

Similar reference characters indicate corresponding parts throughout the several figures of the drawings.

Referring to the drawings, the stop comprises a rectangular base plate 10, having countersunk holes 11 in the corners, by means of which it may be secured to the door 12 by screws 13. A pair of vertically disposed ears or lugs 14 and 15 are provided on the front face of the base, and between these, the same is provided with a rectangular aperture 16, having its upper and lower sides beveled, as at 17 and 18, its upright sides being flush with the inner surfaces of the lugs. A horizontal pivot pin 19 is supported in the lugs, and upon which the check member is hingedly and slidably mounted.

The check member consists of an elongated arm 20, of T-shape in cross-section, having a rectangular block portion 21 at its

and 15, and provided with an inclined elongated slot 22, slidably engaging the pin 19, the slot being at such an angle as to constitute the portion 21 a wedging element, in the inoperative position of the check member (Fig. 3).

At its lower, or ground-engaging end, the check member is bent at a right angle to form a foot portion 23. A stop lug 24 is provided in the plate 10 below the aperture 16, to abut the check member, when in operative position, and thereby prevent its swinging to a vertical position, so that upon soft or uneven ground its effectiveness will be maintained. This stop lug may, if desired, be provided upon the check member, in which case it will abut the base plate, its function and operation being substantially the same however.

The operation of the device is as follows:

When inoperative, the check member is swung to upright vertical position, with its flat surface engaging the front face of the base plate, the inclination of the slot 22, and the weight of the portion 21 causing the same to wedge into place, with the extremity of the portion 21 slightly below the lower edge of the aperture 16, as shown in Fig. 3. The check member is thus self-sustained in its inoperative position, and cannot become accidentally displaced.

In order to move the check member to operative position, it is first raised slightly, so that the extremity of the portion 21 is above the lower edge of the aperture 16 and free to swing therein, whereupon it may be swung downwardly, so that the foot portion 23 engages the ground. In such position the end of the portion 21 is opposed to the upper beveled surface 17 of the aperture, and the force exerted longitudinally of the check member, through its engagement with the ground and support of the door, is directly applied against said surface 17 (Fig. 2), so that a positive and powerful holding action results. The pin 19 acts as a guide, but is relieved of the strain of supporting the door, so that wear thereon and looseness is reduced to a minimum.

The relation of the foot portion 23 to the ground, is such that the angle between the surface of the foot and the ground is relatively small, thereby giving a positive and firm hold thereon. The surface of the foot may either be plain, ribbed, spiked, padded,

adapted for the particular use to which the stop is put.

The lug 24 maintains the angular position of the check member, preventing it from 5 swinging to a vertical and ineffectual position.

I have illustrated and described a preferred and satisfactory embodiment of the invention, but it is obvious that changes 10 may be made therein, within the spirit and scope thereof, as defined in the appended claim.

Having thus described my invention, what I claim and desire to secure by Letters 15 Patent is:

A door stop comprising a base-plate for attachment to a door or the like, a pair of projecting lugs thereon, said plate having a rectangular aperture between said lugs

having its upper surface beveled, a horizontal pivot pin supported on said plate, a check member pivotally engaging said pivot pin at one end and provided at its other end with a ground engaging portion, said check member adapted in its operative position to 20 abut said beveled surface of said aperture, and a stop lug adapted to cooperate with said beveled surface and check member to insure that the check member cannot swing to vertical position when in operative position and to position the check member for 25 engagement with the beveled surface while the check member is in operative position.

Signed at Bridgeport in the county of Fairfield and State of Connecticut this 26th 30 day of June, A. D., 1923.

ALBERT B. GULLY.
